UNITED STATES PATENT OFFICE.

KNUT BERGLOF, OF MONESSEN, PENNSYLVANIA, ASSIGNOR, BY MESNE ASSIGNMENTS,
TO PARENTI MOTORS CORPORATION, OF BUFFALO, NEW YORK.

GAS-ENGINE.

1,324,759.

Specification of Letters Patent.

Patented Dec. 9, 1919.

Application filed February 11, 1918. Serial No. 216,488.

To all whom it may concern:

Be it known that I, KNUT BERGLOF, a subject of the King of Sweden, and resident of Monessen, in the county of Westmoreland and State of Pennsylvania, have invented a new and useful Improvement in Gas-Engines; and I do hereby declare the following to be a full, clear, and exact description thereof.

10 My invention relates to a rotary reversible gas or internal-combustion engine, in which a water-cooled housing with its driving mechanism revolves inside of an elliptical-shaped water-cooled drum; and the objects 15 of my invention are, first, to obtain a continuous rotary motion, thereby gaining energy that is lost in the reciprocating motion of the mechanism in present gas-engines; second, to obtain three or more explosions 20 per revolution, thereby gaining in speed and power; third, to obtain a reverside motion of the engine; and, fourth, to reduce the weight of the engine to a minimum.

I attain these objects by the mechanism 25 illustrated in the accompanying drawings, in which Figure 1 is a side view of the engine; Fig. 2 is an end view of the engine; Fig. 3 is an inside view of a part of the engine showing the mechanism of one of the 30 governors; Fig. 4 is a vertical section of the entire engine; Fig. 5 is an inside view of the covers; Fig. 6 is a horizontal section of the covers on the line 6—6, Fig. 5; Fig. 7 is a section of a part of the engine on the 35 line 7, Fig. 4; Fig. 8 is a section of a part of the engine on the line 8, Fig. 4; Fig. 9 is an inside view of the engine, the cover being removed; Fig. 10 is a section of the 40 revolving housing with its driving mechanism on the line 10—10, Fig. 4.

The engine is considered to be in the same running position throughout the different views and sections and similar numerals refer to similar parts.

45 The elliptical-shaped drum or casing 1 with the two cover-plates 2 bolted to the ends of it constitute the framework of the engine. In the cover-plates 2 turns the shaft 3 with the revolving housing 4 secured to it composed of sectors 4^a with the intervening pockets or recesses 5^a, which contain the six charging chamber-shells 5.

The drum 1 is provided with two mixing 55 chambers 11 one of which is used for exhaust outlet depending on which direction

the engine is running. The gas is conducted to the mixing chamber through pipes 12 and 13 with their respective valves 14. The air is conducted to the mixing chamber through the pipes 13. Openings 15 in the bottom of the drum serve as inlet for the gas and air mixture and outlet for the exhaust. The top is provided with two holes 16 for water intake and outlet, respectively. It is also provided with holes 17 in each end 60 to match holes 18 in cover-plates 2.

Each cover-plate 2 is provided with a semi-annular rib 19 to the right of the vertical center line, the cover being viewed from inside of engine. They also have two annular grooves to receive the packing 70 rings 20, two in each groove, and an annular opening 21 between the grooves for water to pass into the housing. Oil is fed to the engine through a hole from oil cup 22. 75

The shaft 3 secured to the housing 4 is hollow with three radial openings 23 to communicate with radial holes 24 in center of housing, said holes in shaft and housing to allow insulated electric wires 25 to connect 80 the three spark-plugs 6 with circuit-breaker and battery.

The rotary housing 4 is provided with six cover-plates 26 secured to it, said cover-plates being adapted to hold the governing 85 mechanism in place and also to protect the same from water. Oil holes 27 in these plates allow oil to flow in from oil reservoirs 28 in cover-plates 2. Holes 29 are also provided in the plates to form passages for 90 cooling water from opening 21 in the cover-plates 2.

The charging-chamber shells 5 are provided with projecting lugs 30 on the right side viewing them from inside of chamber, 95 said lugs sliding against ribs 19 on cover-plates 2, thus preventing one shell of each pair from sliding out of its pocket during each half revolution of the housing. They are also each provided with two holes 31 to 100 receive the plungers 9.

The cylindrical sector shaped governor-weights 7 secured to the ends of shafts 8 turning in bearings 32 in housing 4 are each provided with a hyperbolic groove 33 receiving a round pin 34 projecting from each plunger 9. The springs 10 secured to the housing have the ends that press on the governor-weights curved and adjusted in such manner as to allow the end of plungers 110

9 to enter the hole 31 in charging chamber shells 5 instantly when engine reaches maximum speed, thus preventing the charging-chamber shell 5 from sliding out of its 5 pocket and receiving another compressed charge, and also to be pulled out instantly when engine has gone down to normal speed.

The engine operates in the following 10 manner:

Considering it to run in the direction indicated on drawings by arrows, open gas-valve 14 to the left in pipe 12, keeping the valve 14 to the right shut. Give the 15 engine a few turns either by hand or some other mechanical starting device. The proper mixture of gas and air is then sucked from inlet pipe 13 through mixing chamber 11 and inlet opening 15 into the engine and 20 compressed against the drum 1 by the next passing charging-chamber shell 5 to the left of centerline, said shell sliding out of its pocket by centrifugal force, the shell 5 to the right being held in its pocket by lug 30 25 on the near side of the shell sliding in the groove 19^a formed by the semi-annular rib 19 on near side cover-plate 2; said compressed mixture being rushed into the charging-chamber.

30 When the center of this charging-chamber is passing the top of elliptical drum 1 about 20 degrees ahead of vertical centerline of engine, the charge is ignited by an electric spark from spark-plug 6 and explosion follows. After passing the sliding face between the drum 1 and housing 4, the 35 charging-chamber shell to the right of centerline, which was considered the left during compression process, now relieved from 40 the sliding contact of its lug against the rib 19 on the near side cover-plate, will slide out of its pocket by centrifugal force, while the shell to the left will remain in its pocket held by the sliding contact between its lug 45 30 and the semi-annular rib 19 on far side cover-plate.

Expansion of the exploded charge will now take place between the ejected shell and the drum, thus forcing the housing to 50 revolve around the axle.

The following charging-chamber shell will force the exhaust-gas out through the opening 15, mixing-chamber 11 and pipe 13.

In reversing the engine, shut valve 14 to 55 the left and open valve 14 to the right, and proceed in the same manner as before. The action of the governors is previously described.

What I claim is:

60 1. In an internal combustion engine, the combination of an elliptical-shaped casing having an inlet and outlet, a shaft, a circular housing mounted on said shaft within said casing, pairs of centrifugally-operated 65 shell-members carried by said housing form-

ing charging-chambers, and means for retaining one of each pair of said shell members in said housing while the other is extended by centrifugal action beyond said housing into contact with the walls of said 70 casing.

2. In an internal combustion engine, the combination of an elliptical-shaped casing having an inlet and outlet, a shaft, a housing made up of sectors, pairs of outwardly-movable shell-members between said sectors, said shell-members forming charging-chambers, and means for retaining one of each pair of said shell-members in said housing while the other is extended by centrifugal action into contact with the walls 75 of said casing.

3. In an internal combustion engine, the combination of an elliptical-shaped casing having an inlet and outlet, a shaft, a circular 80 housing mounted on said shaft in said casing, pairs of outwardly-movable shell-members carried by said housing forming charging-chambers, and means for retaining one of each pair of said shell-members in said 85 housing during each half revolution of said housing while the other shell-member of each pair is extended by centrifugal action 90 into contact with the walls of said casing during each half revolution.

4. In an internal combustion engine, the combination of an elliptical-shaped casing having an inlet and outlet, a shaft, a circular housing mounted on said shaft in said casing, pairs of outwardly movable shell-members carried by said housing forming charging-chambers, projections on said shell-members oppositely-arranged on each pair, and semi-circular guideways on the end-walls of said casing adapted to be engaged 100 by said projections whereby one of each pair of said shell-members is held from outward movement by said guideway during each half revolution, and the other member is extended by centrifugal action into contact 105 with the circular walls of said casing.

5. In an internal combustion engine, the combination of an elliptical-shaped casing having an inlet and outlet, a shaft, a housing made up of sectors mounted on said 110 shaft in said casing, pairs of outwardly-movable members carried by said housing between said sectors forming charging-chambers, means for retaining one of each pair of said shell-members in said housing 115 during each half revolution of said housing while the other member is extended by centrifugal action into contact with the walls of said casing, and speed-governing mechanism contained within said sectors.

6. In an internal combustion engine, the combination of an elliptical-shaped casing having an inlet and outlet, a shaft, a housing made up of sectors mounted on said shaft in said casing, pairs of outwardly- 120 125 130

movable shell-members carried by said housing between said sectors forming charging-chambers, means for retaining one of each pair of said shell-members in said housing during each half revolution while the other shell-member is extended by centrifugal action into contact with the walls of said casing, governor-weights within said sectors, plungers operated by said weights, and adapted to engage openings formed for them in said shell-members.

7. In an internal combustion engine, the combination of an elliptical-shaped casing having an inlet and outlet, a shaft, a housing made up of sectors mounted on said shaft in said casing, pairs of outwardly-movable shell-members carried by said housing forming charging-chambers, means for retaining one of each pair of said shell-members in said housing while the other member is extended by centrifugal action into contact with the walls of said casing, spring-actuated governor-weights mounted in said

sectors, said weights having curved grooves therein, plungers having pins engaging said grooves, and adapted to enter openings formed for them in said shell-members. 25

8. In an internal combustion engine, the combination of an elliptical-shaped casing having an inlet and outlet, a shaft, a circular 30 housing mounted on said shaft in said casing, pairs of outwardly-movable shell-members carried by said housing forming charging-chambers when any one of said pairs reaches the top of said casing, and means for 35 retaining one of each pair of said shell-members in said housing while the other is extended by centrifugal action into contact with the walls of said casing.

In testimony whereof I, the said KNUT 40 BERGLOF, have hereunto set my hand.

KNUT BERGLOF.
